DRAWER FOR ARTICLES OF FURNITURE

Rudolf Abelmann, Himmelpfort, Germany

Application July 7, 1939, Serial No. 283,281
In Germany July 12, 1938

7 Claims. (Cl. 45—96)

This invention relates to a drawer for articles of furniture, such as writing desks, tables for typewriting machines, cabinets, and the like, and its object is to provide minimum space for storing sheets of paper of various grades, forms and the like, and so as to be ready for convenient survey and handling.

The invention substantially resides in that in a drawer, comprising a rear section which is subdivided into cells, and a front section which is pivotally connected to the rear section so that it can be turned down, and is also subdivided into cells, the horizontal bottom boards defining the cells in the rear section are arranged movably and in such manner that their front ends are in a substantially vertical position with respect to each other when the drawer is in its retracted or inactive position, and staggered staircase-fashion toward the front when the drawer is in its advanced or open position.

Preferably, the bottom boards of the rear section are mounted to slide between the side walls of the rear section, and arranged to be shifted to the front together by a coupling engaging all bottom boards.

By these means, it is achieved that in the retracted or inactive position of the drawer in which both sections are within the article of furniture, the bottom boards of the rear section are in their space-saving position, with their front ends positioned vertically above each other, while in the advanced or active position of the drawer the front ends of the bottom boards, being staggered staircase-fashion, present the sheets or forms so as to be readily surveyed, readily accessible and engageable at any time. Therefore, it is possible to provide many cells of comparatively limited height without interfering with the accessibility of the sheets or forms.

A further feature of the drawer which, as described, comprises a rear section and a front section arranged to be turned down about the pivotal connection between the two sections, resides in so arranging the bottom boards defining the cells in the front section, that in the turned-down position of this section they occupy a substantially horizontal, or rearwardly inclined position. In this manner, the cells of the front section are also readily accessible.

With this arrangement, it is of no consequence that the lowermost bottom boards of the rear section are positioned above the upper cells of the turned-down front section when in extracted staircase-fashion. On the contrary, the bottom

boards of the turned-down front section make up a continuation of the staggered bottom boards of the rear section above, and so the cells of the turned-down front section also present their contents of sheets or forms for ready survey and engagement.

A further improvement according to the invention resides in that the bottom boards of the rear section are moved into their staggered or staircase-like positions by means connected to the front section, so that, when the drawer is extracted and during the turning-down of the front section, all bottom boards of the rear section are moved into staggered position together.

In the accompanying drawings, a drawer embodying the invention is illustrated by way of example.

In the drawings,
Fig. 1 is a horizontal section of the drawer,

20 taken on the line I—I in Fig. 2.

Fig. 2 is a vertical longitudinal section of the drawer in retracted position, taken on the line II—II in Fig. 1.

Fig. 3 is a section which is similar to Fig. 2
25 but shows the drawer in advanced position, with its front section turned down.

Fig. 4 is a cross-section on the line IV—IV in Fig. 2.

Referring now to the drawings, the drawer is
30 adapted to be housed in a pedestal forming part of a desk or writing table. 1 is the top plate of the desk, 2 is its rear wall, and 3 are the two side walls of the pedestal. A pair of slide bars 4 are secured to the inner sides of the side walls
35 3 below the space occupied by the drawer.

The drawer comprises a rear section, with a pair of side walls 5, a rear wall 7, and a front section, with a front wall 8 equipped with a suitable handle, a pair of side walls 6, and a bottom 10. A similar bottom might also be provided for the rear section but in the example illustrated a pair of diagonals 9 are provided in place thereof. A sill 11 is inserted between the side walls 5 of the rear section at its front end,

40 and a similar sill 12, of somewhat larger cross-section, is inserted between the side walls 6 at the rear end of the front section. The sills 11 and 12 are made sufficiently large so that they act as braces for the respective sections. The sill 12 of the front section, with its greater width, acts as a support for the sheets in the rearmost cell of the front section when this section is in its retracted position, Fig. 2, so that the sheets will not leave the cell. Secured to the lower sides of the sills 11 and 12 is a hinge 13 which

extends at right angles to the direction in which the drawer is extracted, and permits the front section to be turned down, Fig. 3.

Those portions of the side walls 6 of the front section which are up when the section has been turned down, are cut away along a curve, as shown, or a straight line, from a point 17 toward the joint of the two sections, so that the bottom boards 19 which are loosely inserted in grooves 18 in the side walls 6 of the front section, define cells 20 to 25 of various depths. By these means, the cells at the rear are suitable for smaller sheets, and the cells at the front for larger sheets.

The bottom boards 19 of the front section are so arranged that they are substantially vertical in the retracted position of the drawer, Fig. 2, and are preferably slightly inclined toward the joint of the two sections. Their inclination prevents slipping out of the sheets in the cells when the front section is turned down with a jerk. In the turned-down position of the front section, the bottom boards 19, Fig. 3, are substantially horizontal, or slightly inclined to the rear, so that the sheets in the cells are easily engageable. If desired, partitions in the shape of loose boards 26 may be inserted between the bottom boards 19 in order to subdivide any, or all, of the cells 20 to 25 into two compartments, each for the reception of a set of sheets, and the partitions 30 may be arranged for lateral adjustment.

In order to limit the outward movement of the drawer, an abutment 14 is secured to one of the side walls 5 of the rear section which projects downwardly beyond the corresponding slide bar 4, for cooperation with a check 15 which is secured to the slide bar 4. When the drawer is extracted, Fig. 3, the rear section is arrested by the check 15 and the turned-down front section bears against a buffer on the article. In the example illustrated, the side walls 6 of the front section bear against a bottom board 16 in the pedestal. The drawer cannot now be extracted further, and a return movement is prevented by the turned-down front section.

Bottom boards 27 are mounted to slide in the side walls 5 of the rear section, and are so controlled by means which will be described, that in the retracted position of the drawer, Figs. 1 and 2, their front ends are in a single vertical plane. The bottom plates 27 which are guided between the side walls 5 of the rear section, are connected by a coupling engaging all bottom plates and shifting them to the front staircase-fashion in the extracted position of the drawer, Fig. 3. As best seen in Fig. 4, the bottom boards 27 are mounted to slide in grooves in the side walls 5. Vertical transverse boards 28 are arranged at the rear of each bottom board 27, to act as abutments for the sheets. Partitions 29 extending in parallel relation to the side walls 5 may be provided for subdividing the cells of the rear section, and transverse partitions 30 may also be provided for comparatively small sheets or forms.

In order to more completely utilize the cells subdivided by the transverse partitions 30, such partitions may be secured to slides 31, of wood or sheet metal, which are inserted in the cells. Such an arrangement is illustrated at the right in Fig. 4. When a supply of forms in front has been exhausted, the slide 31 is withdrawn, so that the forms which were at the rear, are now available.

The staircase-like shifting of the bottom boards

27 in the rear section is effected simply by means of a rail 33 at the rear of the rear section by which the bottom boards 27 are coupled. Eyes 32 are secured to the rear ends of the bottom boards 27, and the rail 33 is inserted in the eyes. The upper end of the rail 33 is hook-shaped at 34 and placed on a fulcrum pin 35 at the rear wall 7 of the rear section. This permits of ready detachment from the rail 33, so that the individual bottom boards 27 are easily exchanged, removed, or completed by addition of more bottom plates. This also facilitates the assembling of the drawers. When one of the bottom boards 27 is pulled out, the others will move into the staircase position shown in Fig. 3 since they are all coupled by the rail 33.

Preferably, the bottom boards 27 of the rear section are controlled by the hinged front section. For this purpose, in the example illustrated, a double-armed lever 37 is fulcrumed at the base of the rear section at 38. The lower end of the lever is connected to the front section by a coupling rod 36, and its upper end defines a fork 39, 40 which engages a pin 41 at one of the bottom boards 27. It will appear that upon turning down of the front section, the coupling rod 36 swings the lever 37 about its fulcrum 38 which, through fork 39, 40 and pin 41, moves the bottom boards 27 into their staggered position.

I claim:

1. A drawer for furniture comprising two sections having their bottoms jointed together, said sections consisting of a rear section with horizontal partition boards and back boards and a front section having partition boards with stepped upper ends of which the front section with the boards can swing downwardly through a right angle when the drawer is pulled out, the rear section, when the drawer is closed, having its partition boards with back boards disposed with their front edges vertically superposed said partition boards being slidably guided between the side walls of the rear section, a coupling between the sections, and means whereby the partition boards of the rear section are drawn into a stepped arrangement by the coupling when the drawer is pulled forwardly while the front section in its down turned position is supported on its bottom by a contact surface on the furniture, and the stepped partition boards of the downturned forward section forming a lower extension of the upper steps formed by the withdrawn partition boards of the rear section.

2. A drawer according to claim 1, in which the means includes a coupling bar and the partition boards of the rear section are slidably mounted in grooves in the side walls of the rear section and are retractable all together by means of the coupling bar at the rear connected to said boards.

3. A drawer according to claim 1, in which the means includes a coupling bar and the partition boards of the rear section are slidably mounted in grooves in the side walls of the rear section and are retractable all together by means of the coupling bar at the rear connected to said boards, and each horizontal partition board of the rear section is provided with an eye member whereby the coupling bar is pivotally attached to the rear wall of the rear section and passes through the eye members of the partition boards.

4. A drawer according to claim 1, in which an abutment is provided on the rear section cooperating with a fixed abutment on a slide rail for the drawer.

5. A drawer according to claim 1, in which the means includes a linkage connecting the partition boards of the rear section whereby the movement of the step-wise retractable partition boards of the rear section is derived from the movement of the downwardly turnable front section by means of the coupling.

6. A drawer according to claim 1, in which the coupling comprises a lever intermediately pivoted to the under side of the limitedly retractable rear section and a link, said lever being jointed-

ly connected to the front section by the link and said lever having a forked end co-operating with a pin on one of the partition boards of the rear section.

5 7. A drawer according to claim 1, in which the partition boards of the front section in the down-turned position thereof assume a rearwardly and downwardly inclined position and the upper edges of the side walls of the front section are 10 cut away.

RUDOLF ABELMANN.
